UNITED STATES PATENT OFFICE.

OVE M. NELSON, OF MONTESANO, WASHINGTON.

ANTIGLARE DEVICE.

Application filed March 3, 1923. Serial No. 622,553.

To all whom it may concern:

Be it known that I, OVE M. NELSON, a citizen of the United States, residing at Montesano, in the county of Grays Harbor 5 and State of Washington, have invented new and useful Improvements in Antiglare Devices, of which the following is a specification.

This invention relates to attachments for 10 the headlamps of vehicles whereby to remove or prevent the blinding glare ordinarily given out by headlamps and prohibited by regulations in most localities.

An important object is the provision of a 15 device of this character which is formed as an attachment which may be applied to an already existing headlamp without necessitating any alterations therein and which will efficiently operate to deflect downwardly all 20 the rays of light which normally pass from the lamp in an upwardly inclined direction, the device throwing this light upon the roadway in advance of the vehicle and consequently preventing any blinding glare while 25 improving the illumination where it is needed.

An additional object is the provision of a 30 device of this character which will be simple and inexpensive in manufacture, easy to install, positive in action, efficient and durable in service and a general improvement in the art.

With the above and other objects and advantages in view the invention consists in 35 the details of construction to be hereinafter more fully described and claimed and illustrated in the accompanying drawings, in which:

Figure 1 is an elevation of a headlamp 40 showing my device applied thereto and in section,

Figure 2 is a front elevation and

Figure 3 is a cross section on the line 3—3 of Figure 1.

Referring more particularly to the drawings the letter A represents a headlamp of 45 ordinary construction provided with the usual rim B. In carrying out my invention I provide a hood or casing 10 which is here 50 illustrated as having its upper portion curved as shown at 11 for conforming engagement upon the headlamp and having its lower portion rectangular as indicated at 12. This casing may be constructed of sheet 55 metal or the like suitably painted, enameled

or otherwise treated to present a pleasing appearance and to prevent rusting when exposed to the weather. Secured within the forward portion of this casing is a series of spaced parallel vanes or plates 13 which extend horizontally from side to side of the casing, while secured within the lower portion of this casing are forwardly and downwardly inclined vanes or plates 14.

In order to secure this casing upon the headlamp, I provide a band 15 which embraces the upper portion of the lamp and which mates with a plate member 16 cut away along a curve as shown at 17 for embracing engagement upon the lower portion of the lamp. The band 15 and plate member 16 are connected by bolts 18 which pass through lugs 19 and 20 on the band and plate member respectively. The lower edge of the plate member 16 is formed straight 70 and hinged thereon, as shown at 21 is the bottom 22 of the casing 10, it being preferable that a spring be provided at the hinge for holding the bottom 22 in its normal or horizontal position.

In order that the upper portion of the casing may be secured with respect to the band, I provide a bolt 23 which passes through the band and through a depending ear 24 on the rear edge of the top of the casing, nuts 25 being provided on the bolt for engaging against both sides of the ear.

Assuming that the device has been installed as above described, it will be apparent that the light issuing from the lamp and tending to travel in an upwardly inclined direction, will strike against the horizontal plates or vanes 13 and be reflected downwardly there by so as to fall upon the roadway instead of glaring into the eyes of pedestrians or the drivers of approaching vehicles. As the plates 14 are inclined they do not in any way interfere with the light which passes from the lower portion of the lamp. In this way it will be seen that the light is really concentrated upon the roadway so that far better illumination is obtained than when the ordinary un-protected headlight is used, while at the same time strict compliance with the police regulations of most localities is had.

While I have shown and described the preferred embodiment of the invention it is of course to be understood that I reserve the right to make such changes in the form, con-

struction and arrangement of parts as will not depart from the spirit of the invention or the scope of the subjoined claims.

Having thus described my invention I 5 claim:

1. An antiglare attachment for headlights comprising a plate member formed of detachably connected sections having semi-circular cut out portions mating to define a 10 circular opening for engagement upon a headlamp shell at the outstanding bead at the open front thereof whereby the bead will act to prevent forward displacement, and an open fronted casing hinged upon the 15 lower edge of the bottom section and containing light ray deflecting plates, and means for securing the casing to said lamp engaging plate at a point diametrically opposite the hinge.
2. An antiglare attachment for headlights comprising a plate member formed of detachably connected sections having semi-circular cut out portions mating to define a 20 circular opening for engagement upon a headlamp shell at the outstanding bead at the open front thereof whereby the bead will act to prevent forward displacement, and an open fronted casing hinged upon the 25 lower edge of the bottom section and containing light ray deflecting plates, and means for securing the casing to said lamp 30 engaging plate at a point diametrically opposite the hinge, said means comprising a bolt passing through the lamp engaging

plate, an ear on the rear edge of the casing 35 apertured for the passage of said bolt, and clamping nuts on the bolt engaging against the front and back of said ear.

3. A headlamp attachment comprising a 40 casing adapted to be engaged upon the forward portion of a headlamp and to extend forwardly therebeyond, plates within the casing for reflecting the light downwardly, and means for holding the casing on the headlamp consisting of a band encircling 45 the upper portion of the lamp and detachably connected with the rear edge of the casing, and a plate member connected with the lower portion of the casing and cut away 50 for embracing engagement upon the lower portion of the lamp and detachably connected with said band.

4. An antiglare attachment for headlamps comprising a casing designed to be engaged 55 upon the front portion of a headlamp, means for holding the casing in position, and a plurality of horizontally extending spaced parallel plates within the casing for reflecting downwardly rays of light emerging from the lamp in a normally upwardly inclined 60 direction, and a plurality of upwardly and downwardly inclined plates within the lower portion of the casing, the lower portion of the casing and plate member being rectangular and hingedly connected.

In testimony whereof I affix my signature.

OVE M. NELSON.
